UNITED STATES PATENT OFFICE.

WILLIAM H. G. ELLIS, OF LOUISVILLE, KENTUCKY.

COMBINED UMBRELLA AND CANE.

SPECIFICATION forming part of Letters Patent No. 376,870, dated January 24, 1888.

Application filed June 28, 1887. Serial No. 242,716. (No model.)

To all whom it may concern:

Be it known that I, WILLIAM H. G. ELLIS, a citizen of the United States, residing at Louisville, in the county of Jefferson and State of Kentucky, have invented certain new and useful Improvements in a Combined Umbrella and Cane; and I do hereby declare the following to be a full, clear, and exact description of the invention, such as will enable others skilled in the art to which it appertains to make and use the same.

My invention relates to new and useful improvements in a combined umbrella and cane; and it consists of a cane which can be readily and speedily transformed into an umbrella.

In the accompanying drawings, Figure 1 is a perspective view of my improvement as it appears when used as a cane; Fig. 2, an enlarged vertical section of the smaller end of the same; Fig. 3, a like section of the part between the handle and the staff of the same. Fig. 4 is a vertical section of my improvement when in use as an umbrella; Fig. 5, an enlarged vertical section of the upper end of the same; Fig. 6, a like section of the sliding thimble and a part of the braces and staff of the umbrella; Fig. 7, a like section of the part between the handle and the staff of the same. Fig. 8 is a section through the line $w-z$, Fig. 2, of the point or ferrule d of the cane, which is open, as shown. Fig. 9 is a cross-section of a rib and a brace through the line $x'-y'$; Fig. 3, showing their relative positions when the umbrella is closed.

In the different figures like letters indicate like parts.

A is a tube forming the staff of the cane and the cover of the folded umbrella. B is its handle, which is screwed upon the tube A by means of the threaded sleeve C , attached to B . D is its smaller end, and d is its ferrule.

E and F are beads formed upon the tube, which, when the umbrella is raised, lock the sliding thimble H in position.

G is a rod, made hollow for the purpose of lightness, and g , its upper end, forms the top piece of the umbrella. The rod G serves the purposes of a staff when the tube A is removed for opening and folding the umbrella, and it also serves as a guide to the tube A in transforming the cane into an umbrella.

H is the sliding thimble, having a ring or band, h , formed upon its upper portion, which serves as a stop or check to the lower and smaller joints of the braces K . Four springs, 55 h' , are attached to the lower portion of the thimble H . They are placed at equal distances from each other, and prevent the thimble from slipping downward when the umbrella is raised by clasping the tube A 60 above the bead E . But two of the springs are shown in the drawings.

I are the ribs of the umbrella, and x is a vertical section of one of them.

The braces are formed of two parts, K the 65 larger and K' the smaller, so joined as to have the projection k of the larger part, K , extend beyond the joint. y is a vertical section of the larger part, K , of the braces. By making the braces in two parts the umbrella may be folded 70 very compactly inside the cane, as in Fig. 3.

m are lugs fastened to the sides of the rod G , which bind it to the tube A when my improvement is in use as an umbrella.

n are vertical slots, and o pins in the ferrule 75 d of the cane, Fig. 8. In passing the rod G into the tube A at the ferrule d the lugs m pass through the slots n , and by turning the handle B the lugs m strike the pins o . This binds or locks the tube A and the rod G , with the 80 umbrella-frame attached to it, together.

In practice, when it is desired to change the cane into an umbrella, the handle B is removed from the tube A by unscrewing it at the sleeve C . The umbrella is withdrawn 85 from the tube A by the thimble H , which projects beyond it, and the handle is then screwed upon the tube again. The umbrella is found to be folded upon the rod G . It is partially raised, and the lower end of the rod is pushed 90 into the opening in the ferrule d of the tube A until the lugs m pass through the slots n . A turn or twist is given to the handle B , which causes the lugs m to strike the pins o , thus binding the umbrella-frame to the tube A . 95 The umbrella is now fully raised by pushing upward the thimble H until the projections k of the larger part, K , of the braces strike the bead F , when the ends of the springs h' will pass the bead E and clasp the tube A above it. 100 This locks the thimble H in position. The umbrella is lowered by raising the ends of the

springs *k*' over the bead *E* and pulling the thimble *H* toward the handle *B*; or four slots may be cut in the bead *E*, so that the springs will pass through them on giving the handle a slight turn. When the umbrella is partially raised, the upper portion of the tube *A* and the beads *F* and *E* are readily passed through the thimble *H* in changing the cane into an umbrella. When the umbrella is fully raised, the 10 projections *k* of the larger part, *K*, of the braces pass the bead *E*, but strike the bead *F*, which is larger than *E*, and prevent the thimble *H* from slipping farther upward and the umbrella from turning inside out.

15 To transform the umbrella into a cane, the process is reversed. It is partially lowered and the handle *B* is given a twist or turn in the opposite direction from that mentioned above, which moves the lugs *m*, so that they 20 pass through the slots *n* and release the tube *A* from the umbrella-frame, which is withdrawn from the tube. The umbrella is folded about the rod *G* and passed into the tube after the handle *B* is detached. The operation is 25 completed by screwing the handle upon the tube.

My invention can be cheaply made, and by shaping the ribs and braces as shown in Fig. 9 it forms a combined umbrella and cane that 30 is light and compact, and has all the advantages of both.

It is obvious that my invention is applicable to parasols as well as umbrellas.

Having fully described my invention, what I claim as new, and desire to secure by Letters 35 Patent, is—

1. In a combined umbrella and cane, the combination of the tube *A*, the handle *B*, the sleeve *C*, the beads *E* and *F*, the rod *G*, the thimble *H*, the T-shaped ribs *I*, the jointed and grooved braces *K* *K*', and the top catch consisting of the lugs *m*, the slots *n*, and the pins *o*, substantially as and for the purpose set forth.

2. In a combined umbrella and cane, the 45 combination of the beads *E* and *F*, the thimble *H*, the T-shaped ribs *I*, the jointed and grooved braces *K* *K*', and the top catch consisting of the lugs *m*, the slots *n*, and the pins *o*, substantially as and for the purpose set forth. 50

3. In a combined umbrella and cane, the combination of the tube *A*, the handle *B*, the sleeve *C*, the beads *E* and *F*, and the thimble *H*, substantially as and for the purpose set forth.

4. In a combined umbrella and cane, the 55 combination of the tube *A*, the handle *B*, the sleeve *C*, the T-shaped ribs *I*, and the jointed and grooved braces *K* *K*', substantially as and for the purpose set forth.

In testimony whereof I affix my signature in 60 presence of two witnesses.

WILLIAM H. G. ELLIS.

Witnesses:

HORATIO S. BRIGHT,
JAMES W. BEATTIE.
